UNITED STATES PATENT OFFICE.

GEORGE A. SMITH, OF NEW YORK, N. Y., ASSIGNOR OF SIXTEEN ONE-HUNDRED-AND-FOURTHS TO JAMES W. HENNESSEY, OF NEW YORK, N. Y., FORTY-SIX ONE-HUNDRED-AND-FOURTHS TO ARTHUR LETTS, OF LOS ANGELES, CALIFORNIA, AND TWENTY-ONE ONE-HUNDRED-AND-FOURTHS TO FREDERICK H. WARD, OF BROOKLYN, NEW YORK.

TYPE-BAR MECHANISM FOR TYPE-WRITERS.

No. 879,123.

Specification of Letters Patent.

Patented Feb. 11, 1908.

Application filed December 17, 1906. Serial No. 348,297.

To all whom it may concern:

Be it known that I, GEORGE A. SMITH, a citizen of the United States of America, and a resident of the city, county, and State of New York, have invented certain new and useful Improvements in Type-Bar Mechanism for Type-Writers, of which the following is a specification.

This invention relates to typewriting machines, and particularly to the mechanism by means of which the printing stroke is given to the type-bars through the actuation of the finger-levers.

The object of the invention is to provide a connection between the finger-lever and type-bar which embodies a minimum number of parts and which insures the proper printing movement of the type-bar when the finger-lever is subjected to but little pressure.

With this end in view the invention consists in the novel features of construction and combinations of parts to be hereinafter described and finally recited in the claims.

In the accompanying drawings, in which the same parts are denoted by the same reference characters in both figures, Figure 1 is a vertical longitudinal section of a typewriting machine constructed in accordance with the invention, showing the parts in position of rest, and Fig. 2 is a detail elevation of the type-bar and its actuating mechanism, showing the parts in printing position.

In the drawings 1 denotes the frame of the machine, which is of the usual construction.

The invention resides in the connection between the finger-levers and the type-bars, and hence it will only be necessary to describe one such connection.

2 denotes one of the finger-levers which is pivoted at its rear end within the lower part of the frame 1, as indicated at 3. At the upper portion of the frame there is provided a vertical plate 4 having vertical kerfs in which the type-bars are pivoted.

In the drawing 5 indicates one of the type-bars which is pivoted to the plate 4 by means of a pin 6, so as to be capable of an upward swinging movement into contact with the platen. The type-bar is provided at its pivoted end with an enlargement 5^x which extends beyond and below the pivot-pin 6, as shown.

Extending transversely of the machine at its lower portion, beneath the pivots of the type-bars and above the finger-levers, is a rod 7 upon which are pivoted a number of angle-levers by means of which connection is made between the finger-levers and type-bars.

8 denotes one of these angle-levers. Said lever is formed with a relatively long upwardly-extending arm or branch, and a short forwardly-extending arm having a longitudinal slot 11 therein, the lever being pivoted at the junction of these arms, as shown. The finger-lever 2 is provided intermediate of its length with a laterally-extending pin 12 which enters the slot 11 of the angle-lever 8. The upper end of the angle-lever 8 is considerably enlarged and provided with a curved nose 13. At the forward edge of said nose there is provided a recess 14 and at the rear edge thereof there is a somewhat similar recess 15 having its rear wall formed by a claw or hook-shaped lug 16. The end of this claw or lug is directed toward the front of the machine. When the parts are in their normal position, shown in Fig. 1, the recess 14 at the forward edge of the angle-lever forms a seat for a pin 17 which extends laterally from the enlarged butt-end 5^x of the type-lever, approximately below the pivot 6. In this position the upper edge of the nose 13 is engaged by a second pin 18 extending from the enlargement 5^x of the type-bar at the rear of and slightly below the pivot.

The type-bars are preferably arranged to rest at their forward ends on a ledge 19 extending inwardly from the front-plate of the frame.

The operation of the improved mechanism is as follows: The depressing of the finger-lever causes the forward arm of the angle-lever to be moved downwardly through its slotted connection with said finger-lever and the upper arm of said angle-lever is thus moved forwardly on its pivot. This movement of the angle-lever causes the seat 14 to be disengaged by the pin 17 whereupon said pin rides along the upper edge of the nose 13, thus giving the type-bar a slight upward impetus until the pin 18 thereon is caught by the forwardly and downwardly moving claw 16 and pulled down, as shown.

in Fig. 2, so that the type-bar is pivotally moved into printing position. The movement of the type-bar is almost instantaneous and said bar is given a reliable and effective printing stroke. Upon the release of the finger-lever the parts are immediately returned to their initial position by means of a spring acting in the usual manner upon the finger-lever.

10 The pins which move in contact with certain parts of the device, as hereinabove explained, may, if desired, be provided with small rollers or roller bearings carried thereon as on studs for the purpose of diminishing the friction, and enabling the parts to work more easily and without wear.

Having thus described my invention I claim:

1. In a typewriter, the combination of a 20 finger-lever, a pivoted angle-lever directly connected thereto and movable thereby, said angle-lever having its upper end formed with a nose and with a claw at the rear of the nose and with a recess at the front of the 25 nose, a pivoted type-bar having a pin projecting therefrom to be engaged by the said claw and having a second pin which is engaged by the recess in front of the nose of the angle-lever.

30 2. In a typewriter, the combination of a pivoted type-bar having a pin projecting laterally therefrom at the rear of its pivot and a second pin below said pivot, a pivoted angle-lever shaped at its upper end with

a nose and with a claw at the rear of the nose 35 to engage the said two projecting pins, and a finger-lever operatively connected with the lower end of said angle-lever.

3. In a typewriter, the combination of a pivoted type-bar having an enlargement at 40 its pivoted end, pins formed on said enlargement, a lever formed with a nose and with a claw at the rear of said nose to engage one of the pins and thereby pivotally move said type-bar and being formed also at the front 45 of the nose with a recess to serve at times as a seat for the second pin, and means for actuating said lever.

4. In a typewriter, the combination of a pivoted type-bar having a pin extending 50 laterally therefrom at the rear of its pivot and a second pin below said pivot, of a pivoted angle-lever having its upper end formed with a nose and with a claw at the rear of said nose to engage said first-named pin and thereby 55 pivotally move said type-bar, there being at the front of said nose a recess which serves as a seat for said second pin when the type-bar is in position of rest, and a finger-lever operatively connected with the lower end of 60 said angle-lever.

Signed at New York this 13th day of December, 1906.

GEORGE A. SMITH.
